UNITED STATES PATENT OFFICE.

HENRY C. DIETRICH, OF EVANSVILLE, INDIANA, ASSIGNOR TO CRESCENT STOVE WORKS, OF EVANSVILLE, INDIANA, A CORPORATION OF INDIANA.

COMBINATION COAL AND GAS RANGE.

1,234,642.

Specification of Letters Patent. Patented July 24, 1917.

Application filed July 31, 1916. Serial No. 112,339.

To all whom it may concern:

Be it known that I, HENRY C. DIETRICH, a citizen of the United States, residing at Evansville, county of Vanderburg, and State 5 of Indiana, have invented certain new and useful Improvements in Combination Coal and Gas Ranges, of which the following is a specification.

This invention relates to combination coal 10 and gas ranges.

The present invention has for its object the provision of improvements on the combination coal and gas range of my Patent, 1,198,707, September 19, 1916, and dispenses 15 with the oven dampers and the actuating devices thereof and also the partitions in the burner casings and provides an improved arrangement of heat openings in the side walls of the oven through which heat from 20 the gas burners in the casings may have access to the interior of the oven.

By dispensing with the dampers, the construction is simplified, cheapened, rendered easy to operate and prevented from getting 25 out of order and instead of relatively large amounts of oven space being occupied by portions of the dampers, the entire interior of the oven is rendered available for use.

In the present invention, as in my Patent 30 1,198,707, the valve which controls the flow of gas to the burners in the respective compartments at opposite sides of the oven, also operates means for opening a flue 35 damper so that the heat is taken off from the oven when the gas burners are used. When coal is used, the gas valve being then closed, the flue damper is also closed cutting off communication between the oven and the flue so that, during the use of coal none of 40 the products of combustion can enter the oven and it is heated by contact with the exterior of the walls thereof.

Being aware that changes may be resorted to in carrying out the present invention, the 45 disclosures herein given are to be considered as illustrative, rather than restrictive, of the scope of the invention.

In the accompanying drawings:

Figure 1 is a front perspective of a combination coal and gas range having my improvements, certain parts being removed and others broken away;

Fig. 2, a vertical section;

Fig. 3, a side elevation;

Fig. 4, a rear elevation; and

55

Fig. 5, a detail view, partly in section, of the valve and adjacent parts and its operative connection to the rocker shaft.

Only so much of the combination coal and gas range is shown as will give a clear idea 60 of how my improvements are applied thereto.

The firebox appears at 1, the oven at 2, the usual flue around the oven at 3 by which the products of combustion from the firebox 65 heat the oven without having access thereto, and the take-off flue at 4.

The oven 2 is provided with casings, chambers, or compartments 5 on opposite sides thereof, the one at the left (Fig. 2) 70 being supplied with air in any desired manner, as for instance, by a permanently open port 6. The compartment 5 at the right-hand side of the oven is supplied with air through permanently open ports 7 at the 75 front and rear of the range. The compartments or casings 5 extend substantially the full length of the oven, exteriorly thereof, from front to rear. The upper portion of the compartments 5 are in communication 80 with the central or upper portion of the oven by slots 9. The lower portion of the casings 5 communicate with the lower portion of the oven through numerous holes or openings 10 which are preferably arranged 85 in rows, the rows being one above the other, and all of them below the slots 9. Unlike the side oven walls of the range of my patent aforesaid, the side walls of the oven of the present invention are solid and stationary except for the slots 9 and the openings 10. Rows of lugs 2^a may be provided at different heights on the side walls to support racks or trays, as usual in gas heated 90 ovens.

I have discovered that the oven dampers of my patent aforesaid may be dispensed with and the casings or compartments may remain at all times in communication with the oven 2 through the slots 9 and openings 10. By dispensing with the dampers, not only is the construction simplified and the cost of manufacture greatly lessened, not to mention improvement in respect to liability 100

of derangement, but the entire interior of the oven is unobstructed and much valuable heating space otherwise occupied by the dampers in their movements, is obtained.

5 Contained within the chambers or compartments 5 are gas burners 11 and 12 which are provided with flame discharging slots or openings 13 and 14. The burners extend nearly the full depth of the casings or compartments 5 from front to rear thereof. Each burner directs heat to the slot 9 and openings 10 leading from its compartment 5 to the oven 2.

10 When coal is used instead of gas, the products of combustion, after passing through the flue 3 around the oven, pass out into the flue 4 without having access to the casings 5, and hence such products of combustion cannot enter the oven at any time.

15 While it is desirable to use burners and casings at both sides of the oven, I am aware that only one burner and one casing might be employed.

20 25 At the rear of the oven are exit openings 21 for the outward passage of the heat when the oven is heated by gas, thus insuring free circulation through the oven. The sliding rear damper plate 22 (Fig. 4), is 30 adapted to open or close the ports 21 according to whether the gas valve 23 is opened or closed.

25 At the rear of the range is a sliding bar 24 which carries, or is connected to, the 35 damper 22 and has slots into which project studs or screws 26.

30 At the side of the range is a rock shaft 27 which is suitably mounted in brackets 28 and has a crank end 29 which plays in the slot 30 of a rocker 31 which is pivoted at 32 and has a slot 33 which loosely receives a pin 34 on the bar 24. The valve 23 which controls the admission of gas from the supply pipe 35 to the burners 11 and 12, there being a branch pipe 37 for burner 11, is adapted to turn the shaft 27 when admitting or cutting off the supply of gas to said burners. The arrangement and connections may be those shown in Fig. 5. The 40 valve extends through the casing 36 and has a square socket 37 which detachably receives the squared end 38 of the shaft 27. The air inlet or mixer is shown at 39. When the valve 23 is opened, the rock shaft 27 45 opens the damper 22 so that the heat passes out of the oven when the gas burners are being used. The extent to which the valve 23 is opened will determine, not only the

flow of gas to the burners, but also the extent of opening of the damper 22. The 60 volume of heat and circulation through the oven is thus regulable at will so that any desired heating effect may be obtained when the burners 11 and 12 are lighted.

65 If it is desired to heat the oven by coal, the valve 23 being closed, the damper 22 is thereby closed and the flue 4 is sealed from the oven 2 so that the products of combustion from the firebox cannot enter the oven.

70 Having thus described my invention, what I claim as new and desire to secure by Letters Patent, is:

75 1. In a range, the combination with an oven having permanently open ports communicating with lower parts of the oven 80 and also with parts well above the lower parts of the oven, of a burner casing from which said ports lead, a permanently open air inlet for said casing, a gas burner in said casing adapted to supply heat to all 85 of said ports, and a valve controlling the flow of gas to said burner.

90 2. In a range, the combination with an oven having permanently open ports at lower parts of the oven and also well above the bottom of the oven in different walls thereof, of burner casings from which the ports in the different oven walls lead, permanently open air inlets for said casings, gas burners in said casings adapted to supply 95 heat to all of the ports leading from that casing, and a valve controlling the flow to all of said burners.

95 3. In a combination coal and gas range, a fire pot, an oven, a take-off flue, a heating flue through which the heat may travel from the fire pot to the take-off flue, a burner casing sealed from the aforesaid flues, a permanently open air inlet for said casing, a permanently open port leading 100 from the casing to the oven, a gas burner in the casing, a gas valve controlling said burner, a take-off port connecting the oven with the take-off flue, a damper for said 105 take-off port, and means for automatically opening said damper when the gas valve is opened and closing said damper when the gas valve is closed, whereby when gas is used, the heat is taken off from the oven and when coal is used, the products of combustion are prevented from entering the 110 oven.

115 In testimony whereof, I hereunto affix my signature.

HENRY C. DIETRICH.
